(57) **CLAIM**

The ornamental design for a speaker grille for portable radios, as shown and described.

DESCRIPTION

FIG. 1 is a front perspective view of a speaker grille for a portable radio, showing our new design;
FIG. 2 is a right side elevation view thereof;
FIG. 3 is a front elevation view thereof;
FIG. 4 is a left side elevation view thereof;
FIG. 5 is a back side elevation view thereof;
FIG. 6 is a top elevation view thereof;
FIG. 7 is a bottom elevation view thereof;
FIG. 8 is an alternate front perspective view thereof, shown in a different broken line environment;
FIG. 9 is a right side elevation view thereof;
FIG. 10 is a front elevation view thereof;
FIG. 11 is a left side elevation view thereof;
FIG. 12 is a back side elevation view thereof;
FIG. 13 is a top elevation view thereof; and,
FIG. 14 is a bottom elevation view thereof.
The broken lines shown are included for the purpose of illustrating portions of the speaker grille for portable radios that form no part of the claim.
